HOOK CLOSURE FOR TROUSER FLIES

Samuel Gold, Boston, Mass.

Application July 18, 1950, Serial No. 174,475

4 Claims. (Cl. 2-234)

1

This invention relates to trousers and more particularly to methods of securing hooks to the flies thereof.

It has long been the custom in applying hooks to trousers to hand-stitch such hooks to pieces of tape, which pieces of tape are then secured to the interior or rear flap of a fly by additional hand-stitching. This method has been found slow and costly and, accordingly, it is an object of my invention to provide a method of securing hooks to flies wherein a considerable portion of the labor is done by machine.

It is another object of my invention to provide a method for securing hooks to flies wherein only a portion of such method need be carried out by sewing, and such portion may readily be accomplished on a sewing machine.

It is a still further object of my invention to provide a finished article comprising a hook securely fastened to a fly and using a minimum of material in being so fastened.

It is an additional object of my invention to provide an article comprising a hook secured to a fly wherein such hook is a commercially obtainable article of conventional construction and wherein the mode of securing effects a neat and compact appearance.

In general, my invention contemplates securing a hook by means of a stapling machine to a tab of material and subsequently securing the tab to the inside flap of a fly. Thus it will be apparent that by utilizing a stapling machine, the important and costly step of hand-stitching a hook to a piece of tape is eliminated. Further, the additional step of fastening the tape into the fold of the fly is simplified by machine stitching at an easily accessible edge thereof.

The detailed description of my invention will now be given in conjunction with the appended drawing in which:

Figure 1 is an elevation of the inside upper edge of a fly showing a hook secured in place in accordance with my method.

Figure 2 is an enlarged section through 2-2 of Figure 1, somewhat expanded for clarity.

Figure 3 is a section through 3-3 of Figure 2, but narrowed to more truly show the actual relationship of the elements.

With reference to the drawing, my invention comprises a hook 10 having prongs 13 which are forced through the material of the inner flap 16 at the rear face of the fly. Prongs 13 are provided with slots 20 and I utilize such slots to receive the ends of a staple 23 which impale a

2

cloth securing tab 26 and fasten it to the hook.

The securing tab 26 is then stitched preferably at the line A-A (as shown in somewhat exaggerated form in Figure 3) to flap 16. If desired, the stitch line A-A may continue downwardly (as indicated in Figure 1) for further securing the fly parts together.

A protective tab 30 of cloth or other suitable material is stitched at 32 to the inside flap 16 and to the exterior waist band 35, as seen in Figure 2.

As shown in Figure 3, the stitching line A-A passes through protective tab 30 and into the waist band 35 whence the elements 16, 26, 30, and 35 are integrally secured and whereby hook 10 is firmly fastened to the fly.

In summation, my method consists of first pushing the hook prongs 13 through the inside flap 16, then placing the hook on the anvil of the stapling machine prior to forming the fold 40; then placing the securing tab 26 on the hook, and forcing the staple through these latter two elements whence the staple is clinched on the outer side of the prongs. The protective tab 30 may then be secured at the stitch line 32, or, in fact, may have been previously secured thereto; after which the fold 40 is formed and finally the stitch line A-A provided.

As an article of manufacture it will be apparent that the hook will lie compactly in place interiorly of the fly, and insofar as outward appearances are concerned there is no difference between my method of securing the hook and the previously used but costly hand-stitching method.

I am aware that my invention is subject to change in the sequence of steps followed, and that the economy effected may be obtained by varying the specific arrangement or sequence herein disclosed. For example, the staple 13 can be reversed so that the prongs face in the opposite direction, i. e., directly against the outer face of tab 26. Further, the elements 16, 26, 30 and 35 can be stitched together simultaneously as desired; the practice may vary depending on the particular garment.

Accordingly, I do not seek to be limited to the specific disclosure found herein except as set forth in the appended claims.

50 I claim:

1. In a pair of trousers having a fly portion, said fly portion having a folded edge and an inside flap extending inwardly therefrom, a hook having a pair of spaced apart prongs passing through said inside flap, a securing tab positioned

adjacent said prongs and extending away from said prongs so as to provide an area to be secured to said fly portion, means securing said spaced prongs and said securing tab together, and means securing said inside flap, said securing tab and the outer marginal edge of the fly portion together.

2. In a pair of trousers having a fly portion, said fly portion having a folded edge and an inside flap extending inwardly therefrom, a hook having a pair of spaced apart prongs passing through said inside flap at spaced points, a securing tab positioned adjacent said spaced prongs and extending away from the bight of said hook, means securing said spaced prongs and said securing tab together, and means securing said inside flap, said securing tab, and the outer margin of the fly portion together.

3. In a pair of trousers having a fly portion, said fly portion having a folded edge and an inside flap extending inwardly therefrom, a hook having prong means passing through said inside flap, a securing tab, means for fastening said securing tab to said prong means comprising a staple, said securing tab extending away from said hook so as to provide an area to be fastened to said fly portion, and means for fastening said securing tab to said fly portion wherein said se-

curing tab is intermediate said inside flap and the outer margin of said fly portion.

4. In a pair of trousers having a fly portion, said fly portions having a folded edge and an inside flap extending inwardly therefrom, a hook having spaced and slotted prongs passing through said inside flap, a securing tab, a staple having elements passing through said securing tab and through the slots in respective prongs and being clinched to secure said hook and said securing tab together, and means for fastening said securing tab intermediate said inside flap and the margin of said fly portion.

SAMUEL GOLD.
